UNITED STATES PATENT OFFICE.

LEO A. KRUPP, OF FINDLAY, OHIO.

EXCAVATING MACHINE.

Application filed June 4, 1921. Serial No. 474,882.

To all whom it may concern:

Be it known that I, LEO A. KRUPP, a citizen of the United States, and a resident of Findlay, in the county of Hancock and State of Ohio, have made an Invention Appertaining to Excavating Machines; and I do hereby declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to excavating machines and particularly to those of the open trench digging type.

An object of the invention is the provision of a machine of the class described having 20 a bucket or shovel type of excavating member which is operable to dig a trench at the rear of the machine, which feature is of considerable advantage in digging open trenches either of the narrow type for receiving tile or of the open wider ditch type.

A further object of the invention is the provision, in a machine of the class described, of a bucket or shovel which is operable to entirely clean itself at each load dumping operation so that if operating in clay or other stiff gummy soil the entire load will be discharged from the bucket when dumping.

A further object of the invention is the provision of a simple and efficient machine of the class described which may be used for back filling as well as for excavating purposes. A further object of the invention is the provision, in combination with a boom 35 having a swinging type of excavating bucket attached thereto, of a sight-arm carried by the boom to enable a ditch of predetermined grade to be dug.

40 Further objects and advantages of the machine reside in the efficient and simple bucket and boom control means and in other features thereof, as will appear more fully from the following detailed description.

While the invention, in its broader aspect, is capable of embodiment in numerous forms, a preferred embodiment thereof is 50 illustrated in the accompanying drawings, in which,—

55 Figure 1 is a side elevation of a machine embodying the invention, with the boom shown in full lines in lowered digging posi-

tion and in dotted lines in raised dumping position. Fig. 2 is a top plan view thereof with parts broken away and removed. Fig. 3 is an enlarged fragmentary plan view of 60 the machine with parts in section. Fig. 4 is an enlarged side elevation of the excavating bucket and a portion of its carrying means with parts broken away. Fig. 5 is a top plan view thereof, and Fig. 6 is a 65 rear end elevation of the machine with the boom broken away and with parts removed.

Referring to the drawings, 1 designates the frame of the machine tractor which is supported at its front by wheels 2, mounted 70 to have steering movements; and at its rear, in the present instance, by tractor wheels 3 of the apron or tread belt type, as is common in machines of this character. An upright frame 4 rises from the rear end of the frame 1 and is braced longitudinally of the machine by bracing members 5 extending from the top of the frame 4 forward and downward to the sides of the frame 1. 6 designates a canopy over the machine frame. 75

A vertically disposed mast 7, comprising two laterally spaced upright members rigidly connected together at their ends, is mounted at the rear of the upright frame 4 for horizontal turning movements, and for 80 such purpose is provided with journals at its ends, the upper one being mounted in a bearing bracket 8 projecting rearwardly from the top of the upright frame 4 centrally thereof and the lower one having an axial opening therethrough and being mounted in a bearing 9 provided in the rear cross member 10 of the frame 1. The boom 11 carrying the excavating shovel or bucket projects rearwardly from the machine and is 85 pivotally connected at its inner end to the lower end portion of the mast 7 for vertical swinging movements relative thereto and for horizontal swinging movements therewith 90 relative to the machine frame. The boom 11 in its present construction comprises a pair of horizontally spaced beams rigidly connected together by cross members at suitable points longitudinally thereof. 95

The raising and lowering movements of 100 the boom 11 are controlled by a cable 12, which is connected at one end to the forward end portion of the boom through a bail member 13 pivoted at its forward end to side plates 110 near the forward end portion of the boom for vertical pivotal movements relative thereto. The cable 12 extends upward and

forward from the bail member 13 around a sheave 15 carried by the mast 7 at its upper end, thence extends rearward around a sheave 16 mounted between the legs of the bail member 13, and thence rearward over a sheave 17 secured to the upper portion of the mast 7 and downwardly therefrom below the lower end of the mast 7 through its lower journal and thence under a sheave 18, the axis of which is in a horizontal plane and disposed diagonally of the machine frame. The cable after passing under the sheave 18 extends upward therefrom over a sheave 19, mounted on the upper portion of the upright frame 4, and thence downward and forward to a clutch controlled drum 20 mounted on a shaft 21 journaled in the machine frame 1 cross-wise thereof.

The side swinging movements of the boom 11 are controlled by two cables 22 and 23 connected respectively to the right and left sides of the boom (looking rearward from the machine frame) near the outer end thereof. Each of these cables passes forward between a pair of vertically disposed rolls 24 mounted at the respective outer side portion of the upright frame 4, and thence passes over a respective sheave 25 and forward and downward therefrom with the cable 22 connected to and winding on a clutch controlled drum 26 and with the cable 23 connected to and winding on a clutch controlled drum 27, both drums being mounted on the outer extended ends of the shaft 21.

The bucket or shovel 28 of the machine in which one of the primary features of the invention resides, is of scoop form and has, in the present instance, triangular shaped sides with its connecting bottom portion curved in an arc struck from near the apex portion of the bucket sides. The bucket is provided at its forward end with a cutting nose 29 and has its rear or back side closed by a wall 30. A carrying-arm 31 is fixed to and projects rearwardly from the rear edge of each side of the bucket and a boom arm 32 is projected between the free ends of the arms 31 and pivotally connected therewith, whereby the bucket is carried by the arm 32 for swinging movements longitudinally of the boom. The boom arm rigidly projects downward from the outer end portion of the boom 11 and is secured thereto in the present instance by the side plates 14.

A cleaning blade 34 is pivoted at its upper end within the upper apex portion of the bucket on a shaft 35 mounted therein and extends at its free end to near the curved bottom of the bucket for swinging movements concentric thereto. This blade is adapted to lie in close substantially parallel relation to the back 30 of the bucket and to be moved from such position to near the open front side of the bucket to effect a

cleaning or ejection of material therefrom. The blade has a control arm 36 projecting upward and rearward on an incline from the blade axis; when the blade is in normal position adjacent to the back 30, as shown by full lines in Fig. 4.

The digging cable 37 is connected at the bucket end thereof to the arm 36 of the cleaning blade, thence extends forward therefrom to one of a pair of sheaves 38 mounted between arms 39 projecting upward from the upper end portion of the bucket in line with and forming an extension of the back 30 thereof. The cable thence extends up over one of a pair of sheaves 40 on the boom, and thence down and around the other sheave 38, the cable then extends up over the other sheave of the pair 40 around the rear side thereof and thence forward over a sheave 41 at the lower end portion of the mast 7 down through the center of the mast under a sheave 42 at the lower end thereof and up over a sheave 43, the cable then extending forward under and around the control drum 44 to which it is attached.

The dumping cable 45 is connected at its bucket end to the cleaning blade arm 36, thence extends downward to near the lower end of the bucket back and around a sheave 46 secured to the back, and thence upward over a sheave 47 on the outer end of the boom 11 and forward therefrom around a sheave 48 carried by the mast 7 at its lower end at a side of the sheave 41. The cable 45 passes downward from the sheave 48 through the center of the mast 7 to a point below the same where it passes under a sheave 49 then upward therefrom over a sheave 50 and forward under and around a control drum 51 to which it is secured. The sheaves 42 and 49 are carried at the under side of the cross-beam 10 of the frame 1 with their axes disposed lengthwise of the frame, and the sheaves 43 and 50 are mounted in suitable brackets on top of the cross-beam 10 with their axes cross-wise of the frame. The drums 44 and 51 are loosely mounted on a shaft 52 and each has clutch controlled connection therewith.

It is evident that a drawing in of the digging cable 37 will shorten the space between the forward side of the bucket and the boom 11 and cause the bucket to have a forward and upward swinging digging movement, and that the pull on the cable will exert a forward pull on the arm 36 of the cleaning blade to retain the blade at the limit of its rearward movement. When it is desired to dump the bucket the digging cable 37 is released and permitted to pay out while the dumping cable 45 is drawn in causing a rearward and upward swinging of the bucket to the dumping position shown at the extreme left dotted line position of the bucket in Fig. 1, and at the same time the dump-

ing cable exerts a rearward and downward pull on the arm 36 of the cleaning blade causing a forward swinging of the blade to effect a positive discharge of the bucket 5 contents.

The motor 53 of the machine is mounted on the forward end of the frame 1 and has its shaft 54 extending rearward to a transmission case 55 from which a countershaft 10 56 projects. This shaft carries a gear 57 in mesh with a larger gear 58 on the shaft 21, the gear 57 being shiftable into and out of engagement with the gear 58. A set of gears 59, 60 of different ratio from the gears 15 57 and 58 are mounted respectively on the shafts 56 and 21, the gear 59 being shiftable on its shaft into and out of engagement with the gear 60, and the gear 60 being loose on the shaft 21 and connected thereto in 20 the present instance through a cone clutch 61, one member of which is fixed to the shaft and the other member to the gear. A worm sleeve 62 is mounted on the shaft 21 in loose turning connection with the hub of 25 the gear wheel 60 and is in threaded connection with a bearing 63 fixed to the frame 1. It is thus evident that a turning of the sleeve 62 in one direction or the other will move the clutch member of the gear into 30 or out of engagement with its companion. A sprocket wheel 64 is in driving connection thru a chain (shown in dotted line) with the ring sprocket-wheel of a differential gearing 65 mounted on the sections of a 35 jack-shaft 66, each shaft section having driving connection at its outer end with the respective tread belt 3 thru a chain and sprocket wheel connection 67 (Fig. 1). It is evident that a slow tractive movement, 40 such as desired when digging, may be imparted to the machine when the gears 57 and 58 are in mesh and the clutch 61 is in engagement, and that a faster tractive movement for road traction may be imparted 45 to the machine when the gears 59 and 60 are in mesh and the clutch 67 in engagement.

The drums 20, 26, 27, 44 and 51 are all loose on their respective shafts and engaged thereto by similar clutch means so that a description of the clutch control for one will be sufficient for all. The drum 20 for instance, has the female member of a cone clutch 68 secured thereto, the male member of the clutch being fixed to the shaft. A 55 worm-sleeve 69 has rotatable connection with the outer end of the drum for axial movement therein and is threaded in a bearing sleeve 70 fixed to the frame 1, whereby a turning of the work sleeve within the 60 bearing sleeve will move the drum clutch member into or out of engagement with its companion. The movements of the worm-sleeve 69 are controlled by a hand lever 71 mounted on a rock shaft 72 having 65 a rocker-arm 73 connected by a rod 74 to

a rocker-arm 75 on a rock shaft 76, which is journaled cross-wise of the frame in advance of the shaft 21. A rocker-arm 77 on the shaft 76 is connected by a rod 78 to a rocker-arm 79 on the worm-sleeve 69. The 70 brake-band 80 for the drum 20 is controlled by the rocking of a shaft 81, and a rod 82 connects a rocker-arm on the shafts 81 to a control-lever 83 loosely mounted on the shaft 72. A hand lever 83 controls the 75 clutches of the drums 26 and 27 and for such purpose is mounted on a rock-shaft 84 and has a rocker-arm 85 at one end in connection through a rod 86 with a rocker-arm on the worm-sleeve of the drum 26, 80 while the other end of the shaft 84 has a rocker-arm 87 in connection through a rod 88 with a rocker-arm on the worm-sleeve of the drum 27, the connection between the shaft 84 and drums being such that a rocking of the shaft in one direction will release the clutch engagement of one drum and engage the other and a reverse action will take place upon a rocking of the shaft in the opposite direction. Sleeves 89 and 90 are loosely mounted on opposite end portions of the shaft 84, one being controlled by a hand-lever 91 and being in operative connection through a rod 92 with the brake-band of the drum 26, while the other 95 sleeve 90 is controlled by a hand-lever 93 and is in operative connection with the brake-band of the drum 27 through a rod 94. The brake-band for the tractive controlling clutch 61 is controlled by the rocking of a shaft 95, which has a rocker-arm that is connected by a rod 96 to a control-lever 96^a loose on the shaft 72.

The clutches of the digging drum 44 and dumping drum 51 are controlled from a 100 rock-shaft 97 having a control lever 98, the shaft having connection through a rod 99 and suitable rocker-arms with the worm sleeve of the drum 44, and having connection through a rod 100 and suitable rocker 105 arms with the worm sleeve of the drum 51. A rod 101 connects the brake-band of the drum 44 with a control lever 101^a loose on the shaft 97, and a rod 102 connects the 110 brake-band of the drum 51 with a control-lever 102^a loose on the shaft 97. The dumping drum 51 is preferably larger than the digging drum 44 so that a more rapid dumping movement than digging movement may be imparted to the bucket. The shaft 52 115 is driven from the shaft 21 through a pair of gears 103 and 104 carried respectively 120 thereby.

A sight standard 105 pivotally rises from the outer end portion of the boom 11, having a common pivot, in the present instance, with the bail 13 and having a weight 107 at its lower end to adapt it to normally stand in perpendicular position. This standard has a sight-arm 106 projecting 130

4 laterally therefrom and adjustable lengthwise of the standard to suit the work to be performed.

In the operation of the machine, the boom 11 is lowered by a paying out of the cable 12 from the drum 20 to place the bucket 28 in proper digging position at the bottom of a trench and the dumping drum 51 is then released from its shaft and the digging drum 44 engaged to its shaft to cause a shortening of the digging cable 37 and a consequent forward and upward drawing of the bucket through the arc of a circle to take a slice of soil from the forward end wall of the trench being dug. During this digging operation the pull of the digging cable 37 on the bucket is exerted in part on the arm 36 of the cleaning blade 34 to hold the blade in its retracted position. When the bucket has completed its cut the boom 11 is raised by throwing the drum 20 into operation and thereby effecting a shortening of the cable 12. When the boom has been raised to elevate the bucket above the trench it may be swung to dumping position at the right or left of the trench by engaging one or the other of the boom swinging drums 26, 27. When the bucket is in dumping position the holding brake for the drum 44 is released to permit a paying out of the digging cable 37, and the clutch for the dumping drum 51 is engaged to cause a drawing in of the dumping cable 45 and a consequent rearward and upward swinging of the bucket to dumping position. At the same time the pull of the cable 45 on the arm 36 of the cleaning blade causes a swinging of the blade to the forward end of the bucket to effect an ejection of all matter from the bucket. The boom is then swung back to position over the trench and lowered to digging position by proper control of the swinging cables 22, 23 and hoisting cable 12, the proper digging level being found by sighting across the sight arm 106 and aligning it with sight stakes placed along the line of the trench. This places the bucket in digging operation for the next cut and the digging and dumping are then carried on as before. The machine may be advanced at will by throwing in the advancing connection between the motor and tractor members.

It is evident that the machine may be quickly operated to fill and dump the bucket; that it is effectively and automatically cleaned at each dumping operation of any material which might have a tendency to stick therein, and that the machine may be used to advantage for back filling purposes, although it is primarily intended for use as an excavating machine.

It is also evident that the bucket may be of any width or shape desired to adapt it for digging trenches of different widths and

that a straight bottom trench, which is perfectly level, or inclined if desired, may be dug the same as with an excavating machine of the bucket-wheel or endless bucket chain type due to the sight-arm feature on the boom and the pivotally connecting of the bucket with the boom so that its swinging arc is always of fixed radial length with respect to the boom. 70

It will be understood that while the invention is not limited to the specific arrangement and construction of the parts and combination of elements, shown and described, or to the particular control mechanism for the various cables, as numerous changes may be made without departing from the spirit of the claims. 75 80

Having thus described my invention, what I claim as new, and desire to secure by Letters Patent, is,— 85

1. In a machine of the class described, a bucket having an open front and closed back disposed in lines diverging downward and outward from the top portion of the bucket and having an outwardly curved closed bottom and a cleaner blade pivotally disposed in the bucket for movements front and back of the bucket and having its pivot disposed adjacent to the top of the bucket and substantially concentric to the curve of 90 95 the bottom.

2. In combination, a boom, a bucket carried thereby for swinging, digging and dumping movements, a cleaner member movably carried by the bucket, and separate 100 means operable to impart digging and dumping movements to the bucket and connected to the cleaning member to retain the member in retracted position at the rear of the bucket during digging movements 105 thereof and to impart bucket cleaning movements to the member when the dumping means is acting on the bucket to move it to dumping position.

3. In combination, a boom, an excavating 110 bucket swingingly carried by the boom, a cleaning member pivotally carried by the bucket, means including a cable connected to the bucket and to the member and operable to impart digging movements to the bucket and simultaneously act on the member to retain it in retracted position in the bucket, and means including a cable connected to the bucket and to the member and operable to swing the bucket to dumping position and simultaneously impart bucket cleaning movement to the cleaning member. 115 120

4. In combination, a support, an excavating bucket swingingly suspended therefrom, a cleaner member movably mounted in the bucket, a cable connecting the support and bucket and operable to impart digging movements to the bucket and connected to the cleaner member to normally retain it in re- 125 130

tracted position, and a second cable connecting the support and bucket and operable to impart dumping movements to the bucket and having connection with the cleaner member to move it to eject a load from the bucket during a dumping operation.

5. In combination, a support, an excavating bucket swingingly suspended from the support, and having a closed back and bottom and an open front, a cleaner member pivotally mounted in the bucket and having an arm projecting from its pivot, and two cables connecting the support and bucket and connected to the arm of the cleaner member, one cable being operable to impart digging movements to the bucket and to normally retain the cleaner member in retracted position and the other cable being operable to impart dumping movements to the bucket and at the same time impart a bucket cleaning movement to the cleaner member.

6. In combination, a support, an excavating bucket swingingly suspended from the support, a cleaner member movably mounted in the bucket, and a cable connected to the bucket and cleaner member and operable to impart dumping movements to the bucket and cleaning movements to the cleaner member.

7. In combination, a support, an excavating bucket swingingly suspended from the support, a cleaner member pivotally mounted in the bucket and having an arm projecting from its inner pivot end, and a cable connected to the bucket and to the cleaner member arm and operable to simultaneously impart a dumping movement to the bucket and a cleaning movement to the cleaner member.

8. In an excavating machine, a boom, an excavating bucket swingingly suspended from the boom, separate cable guide means at the upper and lower portions of the bucket back, a cleaner member pivotally mounted in the bucket, separate guide means on the boom, a cable connected to the cleaner member and connecting one guide means of the boom to the upper guide means of the bucket and operable to impart digging movements to the bucket and to retain the cleaner member in retracted position at the rear of the bucket, and a second cable connected to the cleaner member and extending therefrom about the lower guide means of the bucket and the other guide means of the boom and operable to impart dumping movements to the bucket and load discharging movements to the cleaner member.

9. In a machine of the class described, a tractor, a boom pivotally projecting rearwardly from the tractor for vertical and

horizontal swinging movements, separate means operable to control the respective movements of the boom, an excavating bucket pivotally suspended from the boom for swinging movements lengthwise thereof and having its cutting side disposed inward toward the tractor, a cleaner member pivotally carried by the bucket, means operable to impart digging movements to the bucket and retain the cleaner member in retracted position, and means operable to impart dumping movements to the bucket and to move the cleaner member to discharge a load from the bucket.

10. In a machine of the type described, excavating means, cleaning means, associated with the excavating means, and means common to the excavating means and to the cleaning means for imparting dumping movement to the excavating means and cleaning movement to the cleaning means.

11. In an excavating machine, a vertically swinging boom, an excavating bucket carried by and pivoted at a relatively fixed point in relation to and adjacent the outer end of the boom and affording a depth gauging means for the boom, means to operate the bucket and sight means pivotally and directly carried by the boom.

12. In an excavating machine, a vertically swinging boom, an arm rigidly carried by the boom and projecting downwardly therefrom, an excavating bucket pivotally carried by the arm, means to operate the bucket and to permit the lower end of the arm to engage the bottom of the excavation to afford a depth gage for the boom, and sighting means directly carried by the boom and disposed so as to be readable by the operator from the usual station of the latter on the machine.

13. In an excavating machine, a vertically swinging boom, a bucket pivoted to the boom, cleaning means pivoted to the bucket, means connected to said cleaning means and also connected to the bucket to simultaneously operate each, and means for actuating said operating means to effect dumping movement of the bucket and simultaneously therewith cleaning movement of the cleaning means.

14. In an excavating machine, a vertically swinging boom, an excavating bucket pivoted to the boom at a relatively fixed point on the boom, and affording a depth gauging means for the boom, means to operate the bucket, and sighting means carried in its entirety by the boom and disposed so as to be readable by the operator from the usual station of the latter on the machine.

In testimony whereof, I have hereunto signed my name to this specification.

LEO A. KRUPP.
